UNITED STATES PATENT OFFICE.

WILLIAM E. WRIGHT, OF ADAMS, NEW YORK.

CABINET FOR HOLDING ACCOUNT-BOOKS.

No. 827,340.

Specification of Letters Patent.

Patented July 31, 1906.

Application filed March 6, 1906. Serial No. 304,585.

To all whom it may concern:

Be it known that I, WILLIAM E. WRIGHT, a citizen of the United States, residing at Adams, in the county of Jefferson and State 5 of New York, have invented certain new and useful Improvements in Cabinets for Holding Account-Books; and I do hereby declare the following to be a full, clear, and exact description of the invention, such as will enable 10 others skilled in the art to which it appertains to make and use the same, reference being had to the accompanying drawings, and to the letters of reference marked thereon, which form a part of this specification.

15 This invention relates to new and useful improvements in a cabinet for holding account-books; and the object of the invention is to produce a simple and efficient device for taking care of credit accounts, the cabinet 20 adapted to contain a series of hinged leaves having pockets therein, and in the provision of a bail upon one of the leaves adapted to be held in one of a series of corrugations formed in a strip upon the bottom of the casing, 25 whereby one or another of the leaves with pockets may be presented for ready access and adapted to contain account-books.

The invention consists, further, in various 30 other details of construction and combinations and arrangements of parts, which will be hereinafter fully described and then specifically defined in the appended claims.

My invention is illustrated in the accompanying drawings, in which—

35 Figure 1 is a perspective view showing my improved cabinet open and in readiness for access to be had to the books in the pocket of a certain hinged leaf. Fig. 2 is a view of the cabinet closed, and Fig. 3 is a sectional view 40 showing the means for holding the leaves at different angles.

Reference now being had to the details of the drawings by letter, A designates a casing of the cabinet, which is open upon one side 45 and has a hinged end B, to which is fastened a hinged cover C, which has its opposite longitudinal edges flanged, as at C', and adapted to fit over the top of the casing.

D designates a latch which is hinged to one 50 end of the box and has an eye adapted to receive a staple E, fixed to the cover, which staple is designed to be engaged by a hook E' upon the latch.

F and F' designate strips which are hinged 55 together at their meeting ends, and one end of each strip F is hinged to the cover and the

inner end of each strip F' is hinged to the side of the casing.

H H designate a series of leaves each of which is hinged to said hinged end, and each 60 of said leaves contains a series of pockets N, in which account-books are adapted to be held in the manner shown in the drawings. Beginning with the innermost of said leaves the latter are numbered in consecutive order, 65 and the innermost of the leaves has pivotally connected thereto a bail O, the swinging portion of which is adapted to engage one or another of the grooves Q in the corrugated strip R, fastened to the bottom of the casing. 70 Upon said bottom of the casing appear the letters of the alphabet in parallel columns, thereby allowing ready access to be had to the particular books desired.

When the device is closed, it will be noted 75 that the bail will fold underneath the leaves and the cover will form a secure closure for the cabinet.

By the provision of an apparatus as shown and described I have found that credit 80 accounts may be conveniently taken care of in the most rapid and complete manner, affording means whereby the charges and credits may be made directly on the books of the customer, saving the keeping of the usual 85 day-book and ledger and a great amount of work in making out itemized bills for customers. Books kept in a cabinet made in accordance with my invention and which will be readily accessible may be quickly itemized and made ready for settlement and a person may be kept constantly in touch with the 90 accounts and readily ascertain the amount owing from each.

What I claim is—

1. A cabinet for account-books comprising 95 a casing having a hinged end, a cover hinged to said end, straps connecting said cover to the sides of the casing, a series of leaves hinged to said end, and means for holding the leaves at an inclination, as set forth.

2. A cabinet for account-books comprising 100 a casing bearing the letters of the alphabet and having a hinged end, a cover hinged to said end, straps connecting said cover to the sides of the casing, a series of leaves hinged to said end, means for holding the leaves at an inclination, a swinging bail secured to one 105 of said leaves, and a series of corrugations upon the casing adapted to be engaged by said bail, as set forth.

3. A cabinet for keeping account-books

comprising a casing with letters of the alphabet thereon, an end hinged to said casing, a cover, pivotal straps connecting said cover with the sides of the casing, a series of numbered leaves hinged to said end, series of pockets upon each leaf, a bail hinged to one of said leaves, and a corrugated strip upon the bottom of the casing, as set forth.

4. A cabinet for account-books comprising
a casing with the letters of the alphabet thereon, a hinged end, a cover hinged to said end, strips pivoted together and connecting the cover with the sides of the casing, a series of

numbered leaves hinged to said end, pockets in said leaves, a corrugated strip upon the bottom of the casing, a bail pivotally connected to one of the leaves and adapted to engage said corrugated strip, a latch upon said casing, and means for fastening the same to the cover, as set forth.

In testimony whereof I hereunto affix my signature in the presence of two witnesses.

WILLIAM E. WRIGHT.
